GAS DISPENSING DEVICE

Harold L. Norway, Evanston, Ill., assignor to The
Bastian Blessing Co., Chicago, Ill., a corpora-
tion of Illinois

Application October 18, 1940, Serial No. 361,682

27 Claims.

(Cl. 62—1)

The present invention relates generally to liquefied petroleum gas dispensing systems and more particularly to the type of installation in which the storage tank is buried underground where heat present in the ground assists in vaporizing the gas. The embodiment representing the present invention is somewhat similar in certain respects to those shown in the copending William C. Buttner applications filed May 1, 1939, Serial Numbers 271,089 and 271,090, reference to which is hereby made to the extent that a similarity of parts exist between the respective embodiments of the inventions.

The petroleum product employed in the system with which the present invention is concerned, is preferably of the paraffin series, such as butane or propane, or both, and the storage of this fuel is in the form of a liquefied gas which is then vaporized for use in a household appliance.

One way of vaporizing the liquefied gas is the so-called "batch" system in which the vaporization is carried on in the storage tank and the vapor is withdrawn as a gas from the tank. The other way of vaporizing the liquefied gas is the so-called "flash" system in which the liquefied gas is withdrawn as a liquid from the tank and passed through a pressure reducing regulator which causes the liquid to flash into gas.

Wherever the vaporization takes place, heat units are absorbed from surrounding parts and in the batch systems, this refrigerating action is largely expended in the tank whereas with the flash system the heat absorption is concentrated in a comparatively small space, namely around the regulator and the conduits leading therefrom.

Although the present invention will improve vaporization for both systems, it is shown for purposes of illustration in connection with a flash system where heat supply and transfer conditions are found to be more severe.

It is one of the objects of the invention to provide an improved apparatus and arrangement for the vaporization of liquefied gas, and for the re-vaporization of any gas that condenses in the service main.

A further purpose of the invention is to locate in heat conducting contact with an earth-warmed liquid, those parts of the system which are subjected to the refrigerating effect of vaporization. Furthermore, to locate the vaporization regulator where it will be supplied with heat from a convectively circulating body of liquid, preferably the stored liquefied gas, which is exposed to

heat from a surface area of earth greatly in excess of the surface area of parts refrigerated, and more particularly to dispose the vaporization regulator in heat transfer contact with the wall of a container where the wall is largely submerged by an anti-freeze liquid, i. e., a liquid which will not freeze in the expected range of temperatures below the freezing point of water, which liquid is exposed to ground heat so as to prevent excessive frosting and to defrost the regulator rapidly after heavy withdrawal of gas has taken place through the service main.

Another object of the invention is to provide a tank system which is simple in construction and easy to make. More particularly, to provide a tank system in which the parts thereof may be assembled in an improved and time saving manner, and, in this connection, to provide a construction wherein the vaporizing assembly may be installed as a unit in the storage tank, as for example, by inserting the unit through an opening in the wall of the tank.

A further purpose is to provide a tank assembly which can be built as a complete unit at the factory, shipped with minimum danger of damage in transit, and placed in operation readily and easily by connecting the unit to a service main.

It is also an object of the invention to provide a tank system of the class described characterized by an arrangement wherein the withdrawal conduit is disposed below the top of the tank preferably throughout its length, and as a corollary, is insulated from freely circulating atmosphere.

Another object of the invention is to provide an improved filling arrangement for a liquefied petroleum gas system and liquid level gauge, and provide a system which can be standardized and adapted with equal ease for use as a batch or flash system.

A further object of the invention is to provide an improved unitary head for a stand-pipe, and further to provide a slip tube gauge arrangement which will not clog and can be easily manufactured and operated.

These being among the objects of the present invention, other objects will become apparent from the drawing, the description relating thereto, and the appended claims.

Fig. 1 is a side elevation partly in section illustrating an embodiment of the invention in its preferred form.

Fig. 2 is an enlarged transverse section taken upon the line 2—2 in Fig. 1.

Fig. 3 is a further enlarged longitudinal frag-

55

mentary section taken upon the line 3—3 in Fig. 2.

Fig. 4 is a plan view of the cover for the wall or cavity in the end of the tank, and

Fig. 5 is a section showing the improved construction of the head and the slip tube, non-clogging gauge construction.

As already mentioned, the invention is illustrated in connection with the flash system of vaporization wherein liquefied gas is forced from the storage tank by the vapor pressure of the stored fluid gas and is passed through a first stage regulator which reduces the pressure whereby the liquefied gas is vaporized and the resulting vapor is then conducted through a second regulator where it is reduced to the service pressure of 6 ounces per square inch.

In the drawing, a storage tank is indicated at 11 as buried in the earth 12 below the frost line 13 normally expected to exist in the region where the installation is made.

Standpipe construction

A standpipe 14 is provided as mounted by a welded connection 15 where it extends through an opening 16 in the wall of the tank 11. The standpipe comprises an outer casing 17, an intermediate pipe or vent tube 18, a tubular member 21 of a slip tube assembly 22 and a head 23.

The casing 17 supports the head 23 as threaded thereto by taper threads 24 and the vent tube 18 is suspended from the head by threads 25 in a position preferably concentric to the casing 17. The space between the tube 18 and casing 17 is as narrow as possible and the inside diameter of the tube 18 is as large as possible, the relative sizes being determined in relation to the amount of liquid expected to be transmitted between them during a filling operation and the size of a deflector on the tube 18 which will be described later. In this way, the incoming replenishing liquid is spread into the form of a thin, cylindrical liquid column and the interior of the vent tube is large enough to prevent entrainment of splashed liquid. Preferably, the cross sectional area of the liquid column is larger than the area of the tube 18.

The vent tube 18 extends through the hollow interior 26 of the head 23 to connect with a lateral conduit 27 closed at its outlet end by an automatic closing or stem operated vapor return or pressure equalizing valve 28. The space 31 between the casing 17 and the tube 18 opens into a conduit 32 which is closed at its outer end by an automatic closing or stem operated filler valve 33. The valves 33 and 28 open when filler and vent supply hoses respectively (not shown) are connected thereto and liquid is passed to the tank.

Concentricity of the casing 17 and tube 18 enables the operation of threading the head 23 with different threads to be performed in a single operation, both threads having the same lead.

The vent tube 18 extends down into the tank 11 and serves as a frictional skin carrier for the descending cylindrical column of replenishing liquid. However, in providing a quiescent area below the mouth 34 of the vent tube 18, a flexible conical bell-like deflector 35 is provided as made of Duprene and secured to the pipe below the mouth 36 of the casing 17 in any suitable manner, whether by a tight fit as shown, or a threaded collar (not shown). In this way, the incoming stream of liquid is fanned out to such

an extent that little, if any, surface turbulence is caused in the tank.

Slip tube gauge

The slip tube gauge 22 is an improved one as designed to serve several functions that otherwise would require additional parts. The slip tube gauge illustrated functions as will be described later, in detecting any level of liquid in the tank, and when drawn to its extreme upper position, functions in cooperation with the vent tube 18 to warn when the maximum rated or fill level for the tank has been reached, and simultaneously therewith, permit the servicing of the packing around the tube.

The slip tube gauge 22 as shown in detail in Fig. 5, comprises the tubular member 21 slidably mounted to slip up and down through a body 38 as sealed with respect thereto by a packing 41 compressed by a gland nut 42. The lower end of the body 38 is machined to provide a valve seat at 43 and is externally threaded at 44 with a tapered thread which is received in the top of the head 23 where it establishes a seal when tightened.

The tubular member 21 comprises an upper pipe 46 and a lower pipe 47, both threaded into an intermediate connecting collar 48 which carries on the upper side thereof, a washer 51 engaging a seat 43 when the slip tube is raised to its upper limit. Thus, when the washer 51 is raised against the seat 43, such provides a means whereby the compartment in which the packing 41 is located is relieved of tank pressures so that the packing 41 can be replaced or repaired whenever desired.

The length of the lower pipe 47 is such that when the washer 51 engages the seat 43, the mouth 52 thereof is drawn up into the vent tube 18 and above the intended maximum rated level for the tank. In this way the washer 51 and collar 48 serve not only as a means whereby the packing 41 can be replaced with safety, but also serves as a stop determining the upper limit of movement of the slip tube gauge.

The upper end of the gland nut 42 is provided with one of the cooperative elements of a bayonet joint 53 and the head 54 shown threaded to the upper end of the slip tube member 21 as at 55. 50 is provided with the other element of the bayonet joint 53. In this way, upward creeping of the gauge under tank pressure is prevented. The head 54 has a threaded chamber 56 therein separated from the tube member 21 by a partition 57. A hole 58 is drilled through the partition 57 concentrically with respect to the threads in the wall of the chamber and a vent plug assembly 61 carrying a pin 62 surrounded by a washer 63 is threaded into the threaded chamber. The plug and pin are so constructed and arranged that the pin 62 preferably extends through and beyond the hole 58 at all operative positions so that it serves to provide an annular flow area for fluid through the hole 58 which is very difficult to obstruct by loose particles as compared with a conventionally open small drill hole. The pin, by extending through the hole, also serves as a means for cleaning the hole. A laterally extending passageway 65 leads from the chamber 70 56 near the bottom thereof so that gas or liquid may be discharged therethrough when the slip tube gauge is operated to determine the level of the liquid in the tank.

In testing for the liquid level in the tank with the slip tube gauge, the tube is raised to its up-

per limit, the vent plug 61 is loosened until the hiss of escaping gas informs the operator that the gauge is in operation. The tube is then pushed down slowly until liquid discharges from the vent hole at which time a reading is taken from the calibrated markings on the outer surface of the tube and by these, the liquid level is determined. The vent plug is then tightened and if there is no further use for the tube, the tube is lowered and again locked in place by the bayonet joint. The vent plug is provided with a T-handle 66 to aid in its manipulation and a protecting cap 67 is threaded to the body 38 as sealed by a washer 68 which closes the vent hole 71 in the body 38. Thus, when the cap 67 is initially loosened, any discharge of fluid serves as a warning that the slip tube gauge has been leaking and the hole 71 vents trapped pressures which otherwise would blow the cap against an operator.

Referring now to that part of the operation of the slip tube gauge which relates to its function as a means for determining when the maximum rated level has been reached during the filling operation, it has been mentioned that the position of the slip tube gauge for this purpose is its upper limit where the mouth 52 of the gauge is disposed up inside the vent tube 18 a spaced distance above the maximum rated level, which, in the particular embodiment, is represented by 30 the position of the mouth 34 of the vent tube 18 in the tank.

As preliminary to an understanding of this arrangement, it would be well to note at this time some of the physical characteristics of liquefied 35 petroleum gas which have been overlooked in the design of several conventional constructions.

Tanks such as the storage tank 11 are serviced and replenished from a supply tank on a truck. After being placed in operation, the fluid contents of both of these tanks above the liquid level is a condensable vapor. The pressure existing in the tank is the vapor pressure of the fluid at the existing temperature, or in other words, that pressure where vaporization and condensation 40 balance each other at the temperature of the tank.

Thus, when the supply tank (not shown) is connected to the standpipe by hose, the pressures in the two tanks will equalize except for the hydrostatic head resulting in the difference of the levels of the two bodies of liquid. This head will increase the pressure in the lower tank above the vaporization-condensation balance existing, and condensation will tend to take place in the lower tank.

This result is unaffected by the presence or absence of a vent tube and takes place whether any vent tube that happens to be provided, extends into the tank a short distance or not.

As conventionally filled and in order to accomplish a rapid filling the supply tank and the ground tank are generally connected so that vapor displaced in the storage tank by incoming liquid will be conducted to the supply tank to replace with vapor the volume of liquid drained therefrom. The vent tube will become a liquid standpipe having a hydrostatic head the same as that of the supply tank. From this time on, the unbalanced pressures due to the two hydrostatic or artificial heads, particularly if the supply tank is warmer than the storage tank, will cause vapor trapped in the storage tank to condense until there is no more vapor there and the tank is filled completely with liquid.

In conventional systems either the mouth of the slip tube is relied upon to contact directly the rising liquid level in the tank, in which case splashing causes many false warnings to be made since the size of the slip tube is small enough to entrain liquid with the gas, or, the vent tube is separated from the slip tube in which case whichever one has the lower mouth in the tank functions first before the other completes its intended function.

However, with the present invention, and the arrangement made between the slip tube member 21 and vent tube 18, the slip tube gauge will warn the second that the hydrostatic head begins to form, since the mouth of the slip tube gauge is disposed where the hydrostatic column begins to form.

Thus, the present invention provides an improved filling device which more accurately assures the correct filling of the tank in a new and improved manner without any increase in the cost of equipment, but rather through the construction and arrangement of the tubes, casing and head, provides a less expensive structure to manufacture and maintain.

Moreover, with the present invention, if the vent pipe fills before a shut-off is had, the hydrostatic head will immediately clear itself after the filling is completed and the level of the liquid therein will assume the level of the liquid in the tank. Thereafter, the slip tube will have sufficient play between its upper limit and the level of the liquid to check accurately the level of the liquid even though the tank is overfilled and the level of the liquid is well above the mouth of the vent tube. In fact, the upper level of the slip tube mouth 52 could be above the top of the tank, if need be, in those installations where shutoff conditions in the filling operations are difficult to control. An accurate test under any of these conditions could be made with the present construction.

A safety valve is mounted upon the head 23 as indicated at 39 and a pressure gauge is mounted 45 as at 40 so disposed on the side of the head 23 opposite the filling and vent connections 33 and 28 as to be removed as far as possible from the damage during the filling operations, yet be in full view.

Protection for the head 23 and parts attached thereto is provided by encasing the head in a concrete vault 49 that is buried below the surface of the earth where it is filled with burlap or the like, if desired, and covered by a reinforced concrete cap 50 secured in place against tampering as by bolts 59.

Unitary tank assembly

The tank 11 comprises a central cylindrical portion 81 having heads 82 butt welded thereto as at 83. One of the heads 82 has an opening in it, such as the opening indicated at 83, which is of sufficient size to receive therethrough, a unitary assembly 84, that can be secured permanently in place after insertion to provide a unitary tank assembly that can be shipped in commerce with minimum danger of damage.

The unitary assembly 84 in the present embodiment of the invention comprises a shell 85 forming a well 86 in the end of the tank and carrying on a wall 87 thereof an elongated vaporization coil 88 and an eduction tube 81, both of which extend through the wall 87 and are supported thereby in sealed relation by welds indicated at 92.

The coil 88 and eduction tube 91 are mounted upon the wall 87 before the shell 85 is slipped through the end of the tank and are so constructed and arranged that their widest overall dimension clears the opening 83.

After the coil 88 and tube 91 are mounted upon the wall 87 the shell 85 is slipped into place and an outwardly extending flange 93 thereon engages the head 82 marginally around the opening 83 where it is welded in place by a weld line 94.

An excess flow check valve 95 is provided in the eduction tube 91, and, to the flange 96 of the excess flow check valve is connected a shutoff valve 97 which opens through a pigtail or tube 99 to a first stage regulator 98 that is disposed preferably in contact with the wall of the shell 85 as shown at 101. In this way, fluid is carried from the interior of the tank to the first stage pressure reduction and it may be noted at this time that the point at which the eduction tube 91 is secured to the shell 85 is at a mean point which permits the eduction tube 91 to be disposed downwardly to educt liquid, or disposed upwardly as shown by the broken line 102, to educt vapor from the tank. In the first instance, the system would function as a flash system and in the second instance the system would function as a batch system.

The low pressure side of the regulator 98 may be connected directly to a service main leading away from the tank or as shown in its preferred form, is connected to one end of the coil 88 so that chilled fluid leaving the regulator is subjected to the warmth of the liquid in the tank. The coil at its other end is connected to the service line 103 as controlled by manual shut-off valve 104.

By disposing the regulator 98 in the well 86, it is located in a compartment where the refrigerating action taking place is readily dissipated by the warmth of an anti-freeze solution exposed to the heat of the earth.

In order that the regulator 98 will not be permitted to freeze, the vent tube 105 is provided with a glycerin cup 106 to prevent a freezable liquid, such as water, from entering or condensing in the regulator, and further, in order to prevent the outlet conduit of the coil 88 from being chilled, a sleeve 107 of heat insulating material is placed thereon as held in place by the valve 104.

After the valves and regulator are installed at the factory, the well 86 is covered, but preferably not sealed, by a cover-plate 108 which is secured in place by bolts 111 threaded into L-brackets 112 welded upon the inside to the shell 85 at suitable points. An outwardly flared portion 113 is stamped or otherwise provided in the cover 108 to protect the cutoff valve 104 from injury in transit and in the ground and also to receive in a sliding fit 114 a pipe 115 which extends up and into the concrete vault 49. A shaft 116 is disposed in the pipe 115 as packed by insulating material 117 to operate the cutoff valve 104 by means of a handle 118 at the upper end thereof where it is accessible in the vault 49.

Suitable supports are provided for the various parts and one of these comprise a supporting member 121 close to the valve 104 so that rough handling of the handle 118 in the vault will not loosen any of the joints by which the valve 104 is connected to the coil 88 and the service line 103. Furthermore, lugs 122 are provided at the unsupported end of the coil 88 and so arranged as to interlock with each other when the unit is inserted through the opening 83. The lugs 122 sup-

port the free end of the coil against inertial strains due to shocks in transit which might spring the coil and loosen it where it is supported upon the shell 85.

5 The service main 103 leads from the valve 104 into the cellar 123 or space below the first floor 124 of a dwelling. The main 103 when necessary, passes through the foundation 125 at an opening such as that indicated at 126 where it is sealed against the passage of moisture by an annular member 127 preferably made of a workable dense material which can be packed into place. From the main 103, which is preferably sloped toward the tank 11, the vapor is carried upwardly by a riser 128 which leads to a manual cutoff valve 131 mounted on a bracket 132 which supports a shelf 133 upon which is disposed a pressure reducing valve 134 that is connected to the cutoff valve 131 by a pigtail 135.

10 The pressure regulator 134 reduces the vapor to the service pressure of 6 ounces per square inch and the gas is then delivered to an appliance (not shown) by an appliance conduit 136.

15 A vent tube 137 for the regulator 134 is inclined downwardly throughout its length to drain away from the regulator any moisture collected therein and has on the mouth thereof, an insect screen 138.

Operation

20 In operation, once the tank 11 has been filled as already described, a vapor pressure is developed therein by the heat received from the earth and fluid is passed into the regulator 98 where it flashes into vapor, or in event the fluid is vapor already, the regulator 98 reduces the pressure thereof for the service main 103, either to the 6 ounce per square inch pressure, in absence of a regulator such as 134, or reduces the pressure to a higher pressure which is then reduced by a second regulator 134 to the service pressure of 6 ounces per square inch.

25 If the system is functioning as a flash system, the flashing of the liquefied gas into vapor at the regulator 98 creates a refrigeration action at this point which absorbs heat from the regulator body and associated parts. The regulator 98 in turn, is in contact with a wall of the shell 85 where it is submerged below the liquid stored in the tank. The wall will chill and liquid will circulate convectively to carry heat absorbed from the earth to the wall 85 to replace the heat taken by the regulator 98 and thereby assist in supporting the vapor phase of the fuel gas developed. Thus, with the tank in contact with the relatively warm earth over a large area and the regulator in heat exchange contact with a wall submerged in the anti-freeze fluid having a high heat content, sufficient heat is conveyed to the regulator 98 to relieve the refrigerating effect taking place at this stage.

30 Under extra heavy flows of gas, the coil 88 in the tank assists in the initial vaporization and where extreme outside cold might condense the gas in the riser 128 revaporization is had in the coil 88 through the relatively abundant supply of heat available in the liquefied gas.

35 Moreover, with the particular arrangement of the valves shown, in event an emergency takes place such as by fire in the dwelling, the valve 104 and handle 118 provide an outside cutoff. This arrangement provides for a single control point for all outside operations of the tank including a shut-off in the service main without subjecting the eduction conduit to atmospheric temperature.

And, having thus described the invention, it will be apparent that the present invention is readily adaptable to function in various vaporizing systems known in the art.

For these reasons, the present invention provides an improved liquefied gas dispensing apparatus within the intent and purposes of the objects stated and although in some respects it is difficult to account fully for the improved results which are obtained by the method and apparatus, described, it is to be understood that any attempt to analyze the theories which are believed to be responsible for the new and improved results are to be construed not as defining a mode of operation, but merely as a possible explanation of certain physical phenomena which have been observed. Therefore, although a certain preferred embodiment of the present invention has been shown and described herein and ways have also been suggested by which the present invention may be utilized in various systems of vaporization, it will be apparent to those skilled in the art, that various and further uses, modifications and changes may be made without departing from the spirit or substance of the invention, the scope of which is commensurate with the appended claims.

What is claimed is:

1. In a liquefied petroleum gas dispensing system having a storage tank buried below the frost line, a service conduit leading from the tank to an appliance, means for introducing fuel into the conduit at a reduced pressure, said means being in contact with the tank at a point below the fill level of the tank, means providing an air space around the first means sealed from the atmosphere by earth, means for filling the tank remote from said first means, and a coil forming a part of said conduit between said first means and appliance and disposed inside the tank.

2. In a liquefied petroleum gas system having a subterranean storage tank receiving heat from the ground and adapted to be filled from above the ground, a delivery conduit a portion of which is disposed below the top of the tank, said conduit including a dip tube for receiving liquefied petroleum gas under pressure, a pressure reducing regulator in heat exchange contact with the tank below the fill level of the tank and receiving liquid from said tube, and filler material between the regulator and the ground level to prevent atmospheric air from circulating in contact with the regulator, said regulator being accessible when the filler material is removed.

3. In a liquefied petroleum gas system having a subterranean storage tank receiving heat from the ground, a cavity in the tank, a delivery conduit comprising a dip tube for withdrawing liquid fuel from the tank, secured to a wall of the cavity, a pressure reducing regulator in heat exchange contact with a wall of the cavity, and a second pressure regulator reducing the gas to a usable pressure at a point of use.

4. In a liquefied petroleum gas system having a subterranean storage tank receiving heat from the ground, a recess in the tank defined by a wall, a delivery conduit communicating with the tank and extending to a point of use, said conduit comprising a dip tube mounted on the wall of the recess for removing liquid from the tank, a pressure reducing regulator disposed in said recess in heat receiving contact with the wall thereof and a coil mounted on said wall and disposed in said tank.

5. In a liquefied petroleum gas system having a subterranean tank receiving heat from the

ground, a service conduit means for vaporizing a liquefied petroleum gas and having a portion disposed below the top of the tank, said conduit comprising a dip tube for withdrawing liquid from a body of liquid under pressure in the tank, a pressure reducing regulator in heat exchange contact with said tank, below the fill level of the tank, filler material between the regulator and the ground level to prevent atmospheric air from circulating in contact with the regulator, said regulator being accessible when the filler material is removed.

6. In a liquefied petroleum gas system having a subterranean tank receiving heat from the ground, a well in said tank defined by a wall, a service conduit for vaporizing a liquid petroleum gas leading from the wall and comprising an eduction tube mounted in the wall of the well at the vertical center of the tank for withdrawing fluid from the tank, a pressure reducing regulator in the well in heat receiving contact with said wall below the fill level of the tank, a coil mounted on the wall and disposed in said tank, a cover for the well, filler material between the cover and the ground level to prevent atmospheric air circulating in contact with the regulator, said regulator being accessible when the filler material and cover are removed.

7. In a liquefied petroleum gas system having a subterranean tank receiving heat from the ground, a walled well in the tank, a service conduit for vaporizing a liquefied petroleum gas comprising a dip tube mounted upon the wall of the well for withdrawing liquid from a body of liquid fuel under pressure in the tank, a pressure reducing regulator in heat receiving contact with said wall below the fill level of the tank, a cover for the well providing a space between the regulator and the earth and filler material between the cover and the ground level to prevent atmospheric air circulating in contact with the regulator, said regulator being accessible when the filler material and cover are removed.

8. In a liquefied petroleum gas system having a subterranean tank receiving heat from the ground, a service conduit for vaporizing a liquefied petroleum gas comprising a dip tube for withdrawing liquid from a body of liquid fuel under pressure in the tank, a pressure reducing regulator in heat transfer contact with said tank below the fill level thereof, a coil disposed in said tank, means providing a space between the regulator and the earth including a cover plate, and filler material between the cover plate and the ground level to prevent atmospheric air circulating in contact with the cover plate, said regulator being accessible when the filler material and cover plate are removed.

9. A tank construction for a system of the class described comprising a container having an opening in a wall thereof, a flanged well marginally sealed in said opening, brackets secured at the mouth of the well, a removable cover plate for the well secured to said brackets, and a regulator mounted in said well in communication upon one side with the interior of the tank and upon the other side with a service main.

10. For use in combination with a liquefied petroleum gas system, a well shaped housing, a coil secured to a wall of the housing, a withdrawal tube secured to a wall of the housing, a regulator disposed in the housing and interconnecting said tube and one end of the coil.

11. A fuel system comprising a tank buried underground and having a standpipe, a compart-

ment surrounding a part of said standpipe, a housing separated from said compartment by heat insulation comprising earth material, said housing enclosing a regulator and manual shut-off valve, and means for operating said shut-off valve from said compartment.

12. In a unitary tank assembly for storing liquefied petroleum gas a coil disposed in the tank and secured at one end upon a wall of the tank, a lug upon the coil at the other end thereof and a secured lug upon the tank cooperating with the first lug to support the coil against rupturing said securement of the coil under shocks to the tank in transit.

13. For use in combination with a liquefied petroleum gas system, a well shaped housing receiving heat from the earth, a conduit secured to a wall of the housing including a withdrawal tube secured to a wall, a regulator disposed in the housing to receive heat from the earth and interconnecting said tube and one end of the conduit.

14. In a liquefied petroleum gas dispensing system having a storage tank buried below the frost line, a service conduit for conveying fuel to a place of consumption, means for educting fuel from the tank in its liquid phase, means interconnecting the eduction means and said conduit for receiving fuel from the eduction means and introducing it into the conduit at a reduced pressure, said pressure reducing means including a valve body disposed in heat exchange relationship with the contents of the tank below the fill level of the tank.

15. In a liquefied petroleum gas system having a storage tank receiving heat from the earth to maintain a working pressure in the tank when liquefied gas in its liquid phase is present in the tank, a regulator receiving heat from the contents of the tank, means for educting fuel from the tank and delivering it to the regulator, conduit means connected to the regulator and extending from said regulator to a point of use including a section receiving heat from the contents of the tank, and means for insulating the regulator from direct heat exchange with the atmosphere.

16. In a liquefied petroleum gas system having a subterranean storage tank receiving heat from the ground, a compartment on a wall of the tank within the confines of the tank, a delivery conduit comprising a dip tube for withdrawing liquid fuel from the tank and a conduit means having a portion thereof disposed in said compartment, a pressure reducing regulator in said conduit means in heat exchange relationship with the contents of the tank, and a second pressure regulator in the delivery conduit for reducing the gas to a usable pressure at a point of use.

17. In a liquefied petroleum gas system the combination of a tank constructed to hold liquid therein and to receive heat from the earth, a regulator disposed to be in heat exchange relationship with liquid present in the tank, conduit means connected to the inlet of the regulator, and a second conduit means connected to the outlet of the regulator and extending from said regulator to a point of use including a coil adapted to be submerged by liquid present in the tank.

18. In a liquefied petroleum gas dispensing system, a container for burial in the ground to receive heat from the ground and adapted to receive a convectively circulating liquid therein, and a portion of a service conduit including a pressure reduction regulator disposed within the contour of the container below the fill level there-

5 of where it will receive heat from the contents of the tank.

19. In a liquefied petroleum gas dispensing system having a storage tank for storing liquefied petroleum gas, an eduction and service conduit communicating with the tank and adapted to be connected in communication with a gas consuming appliance, a pressure reducing regulator in said service conduit and disposed within the confines of the tank.

10 20. In a liquefied petroleum gas dispensing system, a tank for storing liquefied petroleum gas and having a well carried by a wall thereof and disposed within the confines of the tank, a pressure reducing valve disposed in said well and having an inlet and an outlet, conduit means connecting the inlet to the interior of the tank, a second conduit means connected to said outlet and adapted to be connected in communication with a gas consuming appliance, said second conduit means having a portion thereof disposed in said tank but not in communication with the interior thereof.

20 21. In a liquefied petroleum gas dispensing system having a tank for storing liquefied petroleum gas, said tank having a well carried by a wall thereof and disposed within the confines of the tank, a pressure reducing valve disposed in said well having an inlet, conduit means connecting the inlet to the interior of the tank, closure means for said well movable to permit access to the valve, said closure means being constructed to establish atmospheric pressure in said well and confining the fluid present in said well so that it may circulate convectively when the closure means is in place.

25 22. In a liquefied petroleum gas dispensing system, a tank adapted to be buried in the ground and constructed to receive a liquefied petroleum gas to a predetermined level for storage and dispensing purposes, a well in the tank extending below said level, and service conduit means in communication with the tank including a regulator disposed in said well.

25 23. In a liquefied petroleum gas dispensing system, a tank constructed to receive a liquefied petroleum gas in both its liquid and vapor phases, a well in the tank having a wall extending below a predetermined liquid fill limit of the tank, and a service conduit including a regulator disposed in said well, said regulator being in heat exchange contact with said wall.

30 24. In a liquefied petroleum gas dispensing system having a storage tank buried underground in heat exchange relationship with the surrounding earth and adapted to be filled from above the ground level, a walled compartment within the confines of the tank, a regulator therein, a withdrawal tube connecting one side of the regulator with the interior of the tank, a coil connected to the other side of the regulator and disposed in said tank, and means for connecting the coil to a gas consuming appliance.

35 25. In a liquefied petroleum gas vaporizing apparatus the combination of a tank buried underground to receive earth heat and having a body of liquid therein, and gas dispensing conduit means extending through said tank; said conduit means including a coil disposed in said tank in heat exchange relationship with the contents of the tank, a pressure reducing valve at the inlet of the coil and disposed within the confines of the tank to receive heat from the contents of the tank, a supply conduit for supplying liquefied petroleum gas in its liquid phase under pressure

to the pressure reducing valve, said conduit means also including an element connected to the outlet of the coil and a low pressure regulator in said element, the lowest point in said conduit means between said pressure reducing valve and the regulator being disposed in said tank.

26. In a liquefied petroleum gas dispensing system the combination of a tank having a hole in a wall thereof, a well-shaped housing secured in said opening with the bottom of the housing disposed within the confines of the tank, a pressure reducing valve disposed in the housing, conduit

means carried by said housing connecting the inlet of the pressure reducing valve with the interior of the tank, a second conduit means carried by said housing for connecting the outlet of the pressure reducing valve in communication with a gas consuming appliance.

27. The apparatus as defined in claim 26 in which the second conduit means extends through the tank and arranged to be in heat exchange with the contents of the tank but not in communication with the contents of the tank.
